(57) **CLAIM**

The ornamental design for a vehicle wheel, as shown and described.

DESCRIPTION

FIG. 1 is a front perspective view of a vehicle wheel of my new design;

FIG. 2 is a front plan view thereof; and,

FIG. 3 is a left side view of the first embodiment, the top view, and the bottom view being identical thereto, the right side view being a mirror image of the left side view.

1 Claim, 3 Drawing Sheets

FIG. 1

FIG. 2

FIG. 3
